UNITED STATES PATENT OFFICE.

ROCCO PRONINI, OF SMITH RIVER, CALIFORNIA.

RAIL FASTENER.

Application filed February 18, 1926. Serial No. 89,201.

This invention relates to improvements in rail fasteners.

The primary object of this invention is the provision of an improved construction for the fastening of rails to tie plates and ties.

A further and important object of this invention is the provision of improvements in rail fastening means, preferably adapted to be used in connection with the type of rail fastener set forth in my Patent No. 1,555,382, granted Sept. 29, 1925.

A further object of this invention is the provision of an improved type of rail fastener, which is adapted to be connected upon a tie plate for retaining the rail in position, by means of a rotatable key, and including means to prevent rotation of the key.

20 A further object of this invention is the provision of an improved type of rail fastener adapted to be used in connection with main and guard rails for the securing of the same in place upon a tie or tie plate, in a novel manner.

Other objects and advantages of this invention will be apparent during the course of the following detailed description.

In the accompanying drawing, forming a part of this specification, and wherein similar reference characters designate corresponding parts throughout the several views,

Figure 1 is a cross sectional view taken through the improved rail fastener construction, substantially on the line 1—1 of Figure 2.

Figure 2 is a plan view of a rail, showing the application of the improved rail fastener with respect thereto; the rail fastener construction being partially shown in section to show the novel features of the same over that which is shown in my Patent 1,555,382 above referred to.

Figure 3 is a transverse sectional view taken thru a rail construction as mounted upon a tie, showing the novel fastening means therefor; the rail construction being of that type including a main rail and a guide rail in close proximity, held in secure relation by means of the improved rail fastener construction.

Figure 4 is a plan view of the type of rail fastener construction illustrated in Figure 3.

Figure 5 is a cross sectional view taken substantially on the line 5—5 of Figure 4.

Figure 6 is a plan view of the improved type of bed plate, embodying a part of the rail fastener construction.

Figure 7 is a perspective view of a novel type of fastener.

Figure 8 is a cross sectional view taken substantially on the line 8—8 of Figure 4, showing retaining means to hold the rail fastener from rotation.

Figure 9 is a cross sectional view taken substantially on the line 9—9 of Figure 5.

In the drawing, wherein for the purpose of illustration are shown preferred and modified forms of the invention, the letter A may generally designate that type of rail fastener which is adapted to be used in connection with the securing of a single rail B to a tie C; whereas the rail fastener construction D is of the type adapted to be used for securing both main and guard rails E and F respectively to a tie C.

The fastener construction A preferably includes a bed plate 10; lock fastener constructions 11 and 12 for securing opposite sides of the rail B on the tie plate 10; rotatable keys 13 being used with the fasteners 11 and 12 to secure the latter in place against accidental disconnection.

The tie plate 10 includes the main plate portion 15, having an edge flange 16 downturned for abutment against a side 17 of the tie C to prevent rotation of the tie plate. Inwardly of the top surface of the tie plate 10, and inwardly from the opposite side edges 19 and 20 thereof, the same is provided with guide ways 21, which extend in right angular relation with respect to the run of the rail B, and which at the side 19 edges thereof are provided with overhanging flanges 22, similar to the construction set forth in my patent above referred to.

The rail B is placed upon the tie plate 10, and secured thereon by conventional or special types of spikes 25, as the case may be, so that the heads of said spikes overlap the base flanges of the rail B. The spikes 25 are accommodated in suitable openings provided thru the tie plate, transversely thru the guide ways 21, as set forth in my patent above referred to.

The tie plate at opposite sides of each of the guide ways 21 is provided with downwardly extending key slots 27, adapted to receive rotatable keys 13. The tie plate 10 is recessed upwardly from the lower surface 28 thereof, adjacent each of the key

slots 27, laterally inwardly of the key slots 27, so as to provide overhanging flanges 29, so to speak, beneath which the locking lugs 30 of the keys 13 may engage. These recesses, illustrated at 31 in Figure 2 of the drawing are segmental shaped, and at their ends terminate in abrupt shoulders 32, arranged transversely of the slots 27, and against which shoulders the lock lugs 30 may abut to limit the maximum turning movement of the keys 13.

The fasteners 11 and 12 are of the construction set forth in my patent above referred to, providing a body portion 34, having laterally extending attaching flanges 35 and 36, and an overhanging retaining flange 37 which is adapted to overlap upon the rail flanges to secure the rail in place. The body portion 34 of the fasteners includes suitable guide flanges slidable in the guide ways 21, beneath the overhanging flanges 22, as set forth in my patent above referred to, and the forward end of the body portion 34 is bifurcated to receive the spike shank 25 therebetween.

The attaching flanges 35 and 36 are provided with suitable key slots therethrough for alignment with the key slots 27 to receive the keys 13.

Referring to the keys 13, the same each includes a head 40, having a right angled shank 41 extending therefrom, which at the lower end thereof is provided with the locking lug or lugs 30 above referred to. Each of the heads 40 includes a lateral extension 44, having an opening therethrough countersunk upwardly from the bottom surface of said extension. In this opening a retaining and securing rivet is slidably mounted, having an upper head thereon and a lower countersunk head adapted to seat in the countersunk opening above mentioned, when the head 40 is slid laterally over the attaching flange of the fastener. The lower countersunk headed end of the rivet 40 is adapted to seat in a suitable opening 46 provided therefor in the attaching flange, as illustrated in Figure 1, when the key 13 is in locking position with respect to the placement of its lock lug 30 beneath the retaining flange 29 of the tie plate, and in this position the lock lug 30 of the key 13 is in abutment against one of the shoulders 32 to prevent its further rotational movement.

Referring to the fastener construction adapted to support main and guide rails E and F in adjacent parallel positions, the same includes a bed plate 50, which is illustrated in detail in Figure 6, and of course is elongated transversely of the rails E and F in order to be placed beneath both of said rails.

The rails E and F are arranged upon the tie plate 50, and secured thereto by fasteners 51; 52; and 53; the fastener 51 being ar-

ranged at the outer side of the main rail E; the fastener 52 being arranged between the rails E and F for securing both of them to the tie plate; and the fastener 53 being arranged at the inner side of the guard rail 70 opposite the main rail E.

The fastener construction 51 is of the same type as the fasteners 11 and 12 above described, and the tie plate 50 is suitably grooved at 54 inwardly from one longitudinal edge 55 thereof to receive the fastener 51. The fastener 51 is held in place by means of keys 56, of the same construction as the keys above mentioned, and the tie plate 50 is preferably provided with key slots 58 at opposite sides of the guide way 54 for receiving the keys 56, and more particularly the shanks and the locking lugs 60 thereof. The lock lugs 60 of the keys 56 are adapted for abutment against suitable stop shoulders 61 provided on the tie plate 50, to prevent complete rotation of the keys 56, in accordance with the feature above described for the form of fasteners 11 and 12.

The guard rail fastener 53, is of the type 90 adapted to be rotated to be placed upon the tie plate for securing the rail F in position, and this fastener 53 includes a body 62 with a rail base retaining flange 63 thereon. Depending from the body 62 is a key shank 64 95 having a lock lug 65^a thereon, which is adapted to enter a key slot 65 provided in the tie plate 50; the tie plate 50 below the key slot 65 being suitably recessed to provide stop shoulders 67 against which the lug 65^a may abut to limit the rotational movement of the fastener 53. The fastener 53 also includes a lateral attaching flange 68, being apertured at 69 for receiving a suitable retaining pin 70, of the same type 100 as the retaining pin 45 above described, which is adapted to enter at its countersunk headed end in an aperture 70^a in the tie plate 50. It is of course understood that the retaining flange 63 secures the rail base 119 in position.

The improved fastener 52 presents the essential novelty of the fastener construction D, and is placed in a novel relation on the tie plate 50, between the main and guard rails E and F. This fastener 52 includes a body portion 75, which has reduced guide flanges 76 and 77 at opposite longitudinal edges thereof, and which is furthermore provided with the oppositely extending retaining flanges 78 and 79, thereabove, which are adapted to overlap upon the adjacent base flanges of the rails E and F, as illustrated in Figures 3 and 4 of the drawing, to retain the rails in position. The body portion 75 of the fastener 52 is received within a suitable guide way 80, grooved inwardly of the top surface of the tie plate 50, from an edge 81 thereof; the guide way 80 of course having the overhanging flanges 82 adapted to 120

provide grooves for receiving the guide flanges 76 and 77 above mentioned, so that the fastener 52 is slid into the guide way 80 longitudinally of the rails E and F. The fastener body 75 between the rail flanges is provided with a downwardly extending key slot 85, which is adapted to receive the shank 86 of a key 87. The body 75 is recessed laterally of the slot 85, for receiving the locking lug 89 of the key shank 86, below the retaining flange 90; it being of course understood that the retaining flange 90 is formed by the recess 91 which receives the lock lug 89. The lock lug 89 of the key 87 is adapted to abut against the shoulder 92 at one end of the recess 91, to limit the rotational movement with the key 87. The key 87 includes a head with a lateral extension 94, which has an opening there-through countersunk upwardly from the lower surface thereof, and which opening slidably receives a retaining rivet 95 therein, as illustrated in Figure 8 of the drawing. This retaining rivet 95 at the lower end is provided with a countersunk head 97, adapted to ride upwardly into the lower countersunk opening of the end 94 of the key 87, so that it may be arranged flush with the lower surface of the head, to permit the latter to be turned when the pin 95 is removed from an opening 98 formed downwardly in the body 75 of the fastener adapted to receive the same. It is to be noted that the shank 86 of the key 87 extends downwardly thru suitable openings provided in the body 75 of the fastener 52, and also into a socket opening 99 provided in the tie plate 50.

From the foregoing description of this invention it is apparent that novel fastening means has been provided for retaining rails and guard rails upon ties and tie plates, embodying improvements over the fastener construction set forth in my Patent #1,555,382, granted September 29, 1925.

Various changes in the shape, size, and arrangement of parts may be made to the form of invention herein shown and described, without departing from the spirit of the invention or the scope of the claims.

I claim:

1. A rail fastener comprising a tie plate having guide ways provided inwardly of its upper face and key ways in said plate, retaining fasteners slidable in said guide ways having rail engaging portions and having openings therein for alignment with said key ways, means for securing the tie plate to a tie, and rotatable locking means extending thru the aligning key ways and openings of the tie plate and retaining fasteners for locking the latter in an operative relation to the rail, said key ways of the tie plate having movement limiting shoulders thereon against which the rotatable

locking means abuts to limit the rotational movement of the latter.

2. In a rail fastener the combination with a rail, tie and tie plate, said tie plate having key slots inwardly of the upper surface thereof with lateral recessed portions to provide retaining flanges and lateral abutment shoulders, fasteners for overlapping the rail, and keys rotatably supported by the fasteners having locking lugs adapted to enter the key slots of the tie plate and upon rotation of the keys to be received in the recesses of the tie plate below said retaining flanges, for abutment against the shoulders above mentioned to limit the rotational movement of said keys.

3. As an article of manufacture a tie plate having a key slot inwardly from the top surface thereof, said tie plate below the top surface thereof being laterally recessed into communicating relation with the key slot, said tie plate recess being terminated to provide an abrupt shoulder transversely of the key slot, the tie plate above said recess providing a retaining flange laterally of said key slot.

4. In a rail fastener the combination with a rail and tie, a tie plate having a key slot inwardly of the upper surface thereof, and a second opening inwardly of the top surface of the tie plate adjacent said key slot and spaced therewith, a fastener slidable upon the tie plate for securing the base flange of the rail to the tie plate, a rotatable key supported by the fastener for insertion in the key slot of the tie plate to lock the fastener upon said tie plate, said key having an extension thereon slidable over the top surface of the tie plate, said extension having a transverse opening countersunk upwardly from the lower surface thereof adapted to align with the second mentioned opening of said tie plate, and a retaining pin slidable in the opening of said key having a countersunk head thereon adapted to enter the said opening of the said tie plate when the key is locked on the tie plate for securing the fastener in position, said countersunk head adapted to be received in the countersunk opening of the key to permit the key to be slid for rotational movement.

5. In a fastener construction for securing rails to a tie plate and tie the combination of a tie, a rail, a tie plate, a fastener, means to secure the fastener in sliding relation upon the tie plate, said fastener having retaining flanges adapted to abut the rail base in secured relation upon the tie plate, said fastener having a key slot therein and a lateral internal recess facing said key slot, said tie plate having a socket therein adapted to align with the key slot when the fastener is in place on the tie plate, and a key rotatable in the key slot of the fastener having a lock lug thereon adapted to enter

the internal recess of the fastener to prevent detachment of the key from the fastener, said key including a shank adapted to project thru the key slot of the fastener

5 into the socket of the tie plate to lock the fastener to the tie plate against longitudinal movement.

6. As an article of manufacture a rail fastener comprising a body having a lateral

10 rail retaining flange thereon, said body having a key slot extending transversely therethrough and an internal recess facing in communicating relation with said key slot, said body over the recess having a retain-

15 ing flange, and a key rotatably supported in the key slot including a lock lug adapted to enter the recess of said fastener to prevent removal of the key from the fastener, said key having a shank adapted to project 20 beyond the lower surface of the fastener.

7. As an article of manufacture a rail fastener comprising a body having a lateral rail retaining flange thereon, said body having a key slot extending transversely there-

25 through and an internal recess facing in communicating relation with said key slot, said body over the recess having a retaining flange, a key rotatably supported in the key slot including a lock lug adapted to enter

30 the recess of said fastener to prevent removal of the key from the fastener, said key having a shank adapted to project beyond the lower surface of the fastener, and means for preventing rotational movement of the 35 key.

8. As an article of manufacture a fastener for securing rails upon ties comprising a body having a lateral rail base engaging retaining flange, said body having a key slot

40 extending inwardly of the top surface thereof, said body having a recess therein extending thru said key slot with an overhanging flange above the recess, said recess terminating in an abrupt shoulder transversely of the 45 key slot, and a key including a head, a shank greater in length than the thickness of said body adjacent the key slot, said shank having a lock lug thereon, the shank and lock lug being adapted to be received in the key

50 slot of the body so that the lock lug may enter the recess of the body for abutment against the shoulder thereof to limit the rotational movement of the key, the key when

in such position having its head resting upon 55 the top surface of the body with the shank thereof projecting below the opposite surface of the body.

9. As an article of manufacture a fastener for securing rails upon ties comprising a 60 body having a lateral rail base engaging retaining flange, said body having a key slot extending inwardly of the top surface thereof, said body having a recess therein extending to said key slot with an overhanging flange above the recess, said recess terminating in an abrupt shoulder transversely of the 65 key slot, a key including a head, a shank greater in length than the thickness of said body adjacent the key slot, said shank hav-

ing a lock lug thereon, the shank and lock lug being adapted to be received in the key slot of the body so that the lock lug may enter the recess of the body for abutment 70 against the shoulder thereof to limit the ro-

tational movement of the key, the key when in such position having its head resting upon 75 the top surface of the body with the shank thereof projecting below the opposite surface of the body, and releasable means for

80 securing the head against relative rotational movement upon the body to prevent the lock lug from removal from said recess.

10. In a rail fastener construction the combination of a tie plate, a tie, main and guide 85 rails in spaced parallel relation upon the tie plate, a fastener at the outer side of the main rail detachably secured to the tie plate and holding the rail in position thereon, a fastener detachably secured to the tie plate 90 at the remote side of the guide rail for supporting the latter on the tie plate, said tie plate between the main and guide rails being grooved inwardly of an edge thereof parallel with the main and guide rails, a fastener 95 slidable in said grooves having retaining flanges laterally extending from opposite sides thereof for engaging over the base rails of the main and guide rails, said fastener having a transverse key slot therein, said tie 100 plate having an opening therein for alignment with the key slot, and a detachable rotatable key for the key slot including a shank adapted to enter the opening of the tie plate to retain the said fastener against movement 105 from its guide way.

ROCCO PRONINI.
